MANUFACTURE OF CAPACITORS

Richard Alfred Grouse, London, England, assignor to A. H. Hunt Capacitors Limited, London, England, a British company.

Application September 21, 1951, Serial No. 247,624

Claims priority, application Great Britain July 15, 1948

6 Claims. (Cl. 29—25.42)

This invention relates to the manufacture of roll capacitors of the kind described in the specification of my co-pending U. S. patent application Serial No. 70,237, filed January 11, 1949, now Patent No. 2,637,766, granted May 5, 1953, from which the present application has been divided.

An object of the invention is to provide a process of producing strips of dielectric which bear a series of metallic film electrodes for the purpose of making such capacitors.

My co-pending application aforesaid concerns a capacitor which has for its essential operating portion a strip of metallised dielectric whereof the metallised surface is subdivided by a continuous non-metallised portion extending in a devous course along the strip between separate metallised areas so as to form a repeated pattern in which some metallised areas extend across the strip from one edge and some from the other. When the strip is wound into a roll different metallised areas overlap one another, the areas extending from one edge being connected to one pole of the capacitor and those extending from the other edge being connected to the other pole.

Accordingly, the present invention comprises a process of producing webs of dielectric which bear a series of metallic film electrodes some of which extend from one edge of the web and some from the opposite edge, for the purpose of making capacitors, consisting in taking dielectric web material which is metallised on one face, passing it continuously into contact with a crenellated periphery of a demetallising roller while maintaining the metallised face at a potential sufficiently different from that of the demetallising roller to ensure that, notwithstanding the variations of rate of discharge due to the crenellation of the roller, at the point of coming into contact between the surfaces of the metallised dielectric and of the crenellated periphery, there is a passage of electric current sufficient to demetallise all that part of the surface of the dielectric which comes into contact with said periphery and to leave the said electrodes electrically isolated from one another between the crenellations.

It is to be understood that the expression "crenellated periphery" which is employed in this specification and claims is intended to describe broadly the shape of the periphery of the roller which is scolloped or notched, or otherwise hollowed out, so as to have a ridge of metal along the edge which deviates left or right, such ridge may follow a square or key pattern or a curved or scolloped pattern although for reasons of efficiency the square pattern is preferred.

In a preferred form of the invention the dielectric web material is passed into contact with a demetallising roller, the crenellated periphery of which is so shaped as to come into contact with the dielectric along a course which forms a repeating pattern along the length of the dielectric, the pitch of which pattern increases from one

2

end towards the other end of the dielectric. The repeating pattern may be in the form of a narrow band which deviates alternately towards each edge of the dielectric as it extends along the length of the web. The narrow band may, for example, follow a square key-pattern along the length of the web. The demetallising roller may, however, have a crenellated edge shaped to come into contact with the dielectric along a course which forms other repeating patterns in order to provide particular arrangements of electrodes.

According to a feature of the invention the dielectric web material may be brought into contact with the demetallising roller by leading the dielectric around a substantial portion of the periphery of the roller.

According to a further feature of the invention the dielectric web material may be of a length sufficient for the manufacture of a number of capacitors, the dielectric, after demetallisation, being wound into a roll which is later taken and lengths of strip unwound from it on to a mandrel to form individual capacitor rolls, which mandrel is such that after winding a capacitor roll the roll can be slipped off the mandrel endwise and a further roll started thereon. Preferably the dielectric has been demetallised according to a repeating pattern, the pitch of which increases along the dielectric, and the mandrel used is of such diameter that the repeats of the pattern fit the circumference of each turn of the roll.

The following is a description by way of example of one process of manufacture in accordance with the invention, reference being made to the accompanying drawings in which:

Figure 1 is a representation of one form of metallised dielectric strips for winding into a capacitor in accordance with my co-pending U. S. application No. 70,237 now Patent No. 2,637,766, granted May 5, 1953;

Figures 2, 3 and 4 are representations of other such strips;

Figure 5 is a perspective view of a demetallising apparatus for carrying out the process in accordance with the present invention;

Figure 6 is a perspective view of a demetallising roller used in the apparatus of Figure 5;

Figure 7 is the circuit diagram of the apparatus shown in Figure 5, and

Figure 8 is a diagram of a winding apparatus for winding a strip of demetallised dielectric into a capacitor roll.

Referring to Figures 1 to 4, these show portions of paper dielectric strips which bear a series of metallised areas. Such strips are shown in my co-pending U. S. patent application Serial No. 70,237, now Pat. No. 2,637,766, granted May 5, 1953, and in accordance with that invention when any one strip is wound into a roll, a capacitor is formed:

The strip 11 shown in Figure 1 is covered with metallised areas 12 which extend from one edge 13 of the strip, and which alternate with metallised areas 14 extending from the other edge 15. The metallised areas 12 are separated from the areas 14 by a narrow demetallised band 16 which follows a key pattern, repeating itself continuously along the strip. The pitch of the repeats of the key pattern gradually increases, being smallest at the beginning of the pattern at 17 on the band and longest at the end of the pattern at 18. The paper is completely demetallised on the end portions 19 beyond the key pattern so as to form plain paper end strips which can be used for the first few turns and the last few turns when the strip is wound into a capacitor roll.

The increase in pitch of the repeats of the key pattern demetallised band 16 is co-related to the thickness of the

paper of which the strip is made, so that if the strip 11, commencing near the end 17 of the pattern, is wound on a mandrel of a particular size, each metallised area plus the width of the demetallised band which cuts it off from the next metallised area just occupies the turn of the roll in which it is wound. Therefore, each of the areas 12 will be exactly overlaid in the next turn with an area 14, and if in the completed roll the areas 12 are connected to one pole of the capacitor and the areas 14 to the opposite pole, the result will be a capacitor in which the alternate areas 12 and 14 exactly overlap one another.

The strip shown in Figure 1 comprises comparatively few areas 12 and 14, and in Figure 2 there is shown a strip comprising a much larger number of areas 12 and 14 succeeding one another and separated by a key pattern as in the case of Figure 1. In Figure 2 the strip is too long to be shown in a single piece and has been subdivided into three portions, the chain lines 20 serving to indicate how in actual fact the one portion is joined on to the other.

Where a capacitor is required to work on a higher voltage than the capacitor above referred to, it is possible to use a strip which is demetallised as shown at 70 in Figure 3. Widely spaced metallised areas 71 extend from the edge 72 of the strip and intermediate metallised areas 73 extend from the edge 74. The large demetallised areas between the metallised areas allow for extra turns of non-metallised dielectric between successive metallised turns of the capacitor.

Another form of strip is shown in Figure 4 and bears metallised areas 81, 82 and 83 which are separated by a demetallised portion 80. As described in my co-pending application aforesaid, when this strip is wound into a roll the result is the equivalent of two capacitors in series with one another.

The strips shown in Figures 1 and 2 can be produced in accordance with the present invention, by the apparatus shown in Figures 5 to 7. Referring to Figure 5, upon a base 21 there is an upstanding support 22 for a number of horizontal spindles which include a spindle 23 on which is mounted for rotation a demetallising roller 24. The roller 24 has a hub 25 made of insulating material in which is a bush 26 to run on the spindle 23. A stem 27 projects from the support 22 and carries an insulating bush 28 on which is mounted a brush holder 29 which supports a brush 30 made of flexible Phosphor bronze strip which bears on the face of the roller 24, and is connected by a wire 31 to a source of electric current.

Also mounted upon the support 22 is a spindle 32 parallel to the spindle 23, and serving to support a roll 33 which consists of a long strip of metallised paper. This is wound on a Bakelite core member 34, and the core member forms a hub which is slipped over a bush 35. The bush 35 runs on the spindle 32, and is pressed against a shoulder on the spindle by means of a spring 36 on the end of the spindle held in place by a nut 37. The bush 35 is screwthreaded on its external surface, and a nut member 38 upon it serves to screw the Bakelite core 34 against a flange formed on the other end of the bush 35 behind the roll 33. Therefore, the roll is held firmly on the bush 35, and is positioned accurately as to its plane by the pressure of the spring 36 against the bush. The strip of metallised paper is led off the roll 33 as shown at 40 and is led around guide rollers 41, 42, 43 and thence around the demetallising roller 24. From the demetallising roller it passes around a guide roller 44 on to a wind-up roll 45. The guide rollers 41, 42, 43 project from a casing 46 which houses ball races to support the rollers so that they turn over easily. The metallised face of the paper strip 40 is arranged to come in contact with the demetallising roller 24, and it will be observed that the same metallised face will be in contact with the roller 42. The roller 42 is connected through

the metal support 22 to earth, and therefore there will be a potential difference between this face of the paper and the demetallising roller 24 which, as before described, is connected to an electrical supply. As can be seen from the connection diagram, Figure 7, the electric supply is connected through a resistance 47 to the brush 30 by way of the line 31, and there is a capacitor 48 which connects the brush 30 to a line 49 leading to the roller 42 and earth. These connections are similar to those described in U. S. application No. 679,532, now Patent No. 2,549,966, granted April 24, 1951, for the demetallising process therein described although in this instance the values of the resistance and capacitor have to be such as to meet the requirements of the variations in the rate of electrical discharge due to the shape of the edge of the demetallising roller 24, this roller being described in detail later. As the metallised surface of the paper strip 40 meets the surface of the roller 24, the electrical discharge which takes place between the roller and the metallised surface removes the metallisation from the surface of the paper without, however, burning the paper itself. The metallisation upon the paper is exceedingly thin as referred to in the aforesaid application Ser. No. 679,532, now Patent No. 2,549,966, granted April 24, 1951, namely about 80 millimicrons of aluminium. The paper itself is only about 8 microns thick but is not burnt by the discharge.

The wind-up roll 45 is mounted on a bush 50 on a spindle 51. A nut 52 on the bush 50 serves to tighten the hub 53 of the roll 45 on the bush, and the bush is held frictionally to the spindle 51 by the pressure of a spring 54, the construction of these parts being similar to the construction of the bush 35 on the spindle 32 already described. There is however a difference in that the spindle 51 instead of being stationary is made rotatable in a boss 55 on the support 22, and is driven at a suitable speed by a pulley mounted on the spindle 51 at the rear side of the support and not appearing in Figure 5 of the drawing. Therefore, the strip 40 will be frictionally driven from the spindle 51 and drawn through the apparatus, but owing to the friction drive afforded by the spring 54 there will be no tendency to snatch or tear the strip 40 when starting the apparatus. It is found desirable to make the earthing roller 42 of a smaller diameter than the other guide rollers, and to determine its exact diameter experimentally to suit the exact running conditions of the machine, so that the metallised paper gets a suitable pressure upon the earthing roller, which is sufficient to ensure that no demetallisation takes place at the surface of the earthing roller itself without being so great as to cause rupture of the paper strip. As will be seen in the drawing, the roller 42 is shown as being of smaller diameter where the strip 40 passes around it, and in practice if any tendency is found to an electric discharge at the contact between the roller 42 and the metallised surface, the diameter of the roller 42 is reduced until it is found that such discharge disappears, because any discharge at this roller would tend to demetallise the paper all over its surface and would, by the partial removal of the metallised surface, reduce the capacity of the capacitors which are the eventual product of the manufacture.

The periphery of the demetallising roller 24 is formed with a pattern which corresponds to the key-pattern shown in Figures 1 and 2. The roller as shown in detail in Figure 6 of the drawing has a key-pattern edge 56 corresponding to the demetallised key-pattern of the line 16 of Figure 1. This extends part of the way round the roller, and the remaining surface of the roller has a plain cylindrical surface shown at 57 and serves to produce the completely demetallised portions 19 of the strip 11 of Figure 1. It will be noted that the key-pattern portion of the edge 56 is made by milling out from the edge a number of notches 58 which run out into one face of the roller and by milling out between them other

notches 59 which run out into the opposite face of the roller. The notches 58 can be rapidly machined by a plain cylindrical milling cutter, but if similar notches were cut in the opposite face of the roller, as they will be of constant width, they would tend at the portion which lies nearest to the axis of the roller 24 to run into the metal of the notches on the opposite side, or to make the walls between the notches unduly thin. The notches 59 are therefore cut with an end milling cutter, and have a cylindrical bottom as can be seen clearly from the drawing. In order to balance the roller and allow for the removal of metal which has taken place in cutting the notches 58, 59, a certain amount of metal is removed by shallow drill holes 60 on the opposite side of the roller near the circumference. The roller is very carefully balanced because it has to be driven by means of the pull exerted by the weak paper strip 40.

For producing a strip such as the strip shown in Figure 2 of the drawing a similar roller to the roller 24 of Figure 6 is used, but the key pattern notches 58, 59 are continued around the greater proportion of its circumference and it is one of the features of the apparatus shown in Figures 5 to 7 inclusive that an appropriate pattern of roller can be provided for all the designs of capacitor which are to be made within a wide range, and in order to change from producing paper suitable for one design of capacitor to paper suitable for another design, all that is necessary is to change the demetallising roller, substituting for it another roller of the same diameter but different design and leaving all the adjustments of the apparatus untouched.

After the strip 40 has been wound into the roll 45 until the roll is full, the roll 45 is removed from the apparatus and capacitors are then wound therefrom on any suitable winding apparatus. This may be much simpler than ordinary apparatus for winding paper condensers, and preferably comprises a short stub-mandrel such as 60, Figure 8, which projects from a gear box 61 and is driven by a V-grooved pulley 62 on a driving shaft 63. The strip 40 is wrapped by the operator around the stub-mandrel 60 for the first turn by hand, and then the apparatus is started up and a condenser roll 64 is wound up thereon. As will be appreciated there would be a suitable support for the roll 45 from which the strip 40 is unwound, and ordinarily it would be passed around one or more tensioning rollers on its way to the mandrel 60. The mandrel 60 may have a flat face such as is indicated at 65 to assist in driving the paper strip when the roll 64 is being built up.

As soon as a condenser roll is completely wound on to the mandrel 60, the end turn is stuck temporarily down by a patch of adhesive or by a spot of grease or otherwise, and the condenser roll is slipped endwise off the mandrel, the end of which is left free, as shown in Figure 8 for the purpose and then the winding of a further capacitor upon the mandrel can commence without delay.

The completed rolls are sprayed on the ends in a similar way to that described in U. S. patent application No. 490, now abandoned, to afford a base of sprayed copper or the line to which terminal wires or terminal caps may be soldered. In practice the diameter of the stub-mandrel 60 may be very small, say $\frac{1}{16}$ or $\frac{3}{64}$ of an inch, from which the small size of the capacitors producible in accordance with the invention may be gauged. Capacitors $\frac{1}{10}$ of an inch in diameter and $\frac{1}{4}$ of an inch long are easily producible according to this invention, and using the paper 8 microns thick will have a capacity of about 0.01 microfarad. If the thickness of the paper is increased to 15 microns the capacity may be reduced to 0.003 microfarad. In the former case the capacitor will stand a voltage of 150 volts, while with paper 15 microns thick the capacitor may withstand 350 volts, using varnished paper in both cases.

It will be appreciated that although the above descrip-

tion relates specifically to producing the strips of dielectric shown in Figures 1 and 2, the strips shown in Figures 3 and 4 may be produced by the same process using a suitably shaped demetallising roller. Instead of the key-pattern edge 56 of the demetallising roller 24, the edge of the demetallising roller for producing the strip shown in either Figure 3 or Figure 4 would be shaped to correspond to the respective pattern of demetallisation which is required on the strip.

It will be further understood that the strips of dielectric described herein as being produced by the process according to the present invention, are by way of example only. Other, and more complex patterns of demetalled dielectrics may be successfully produced in accordance with the invention.

I claim:

1. A demetallising roller having a crenellated periphery for use in a process of producing from dielectric web material metallised on one face, webs of dielectric which bear a series of metallic film electrodes.

2. A process for the production of electrical capacitors, comprising the steps of taking thin flexible dielectric web material that is metallised all over one face, demetallising a band extending continuously along the web which band deviates from side to side of the web thereby subdividing the metallisation into a series of metallic film electrodes forming a repeated pattern in which some of said electrodes extend inwardly from one edge of the web and others extend inwardly from the opposite edge, those electrodes terminating at one edge of the web being electrically insulated by the demetallised band from the electrodes terminating at the opposite edge, spirally winding a single length of said web material so demetallised into a close-wound roll, the electrodes obtained by the demetallisation being so arranged that after winding the electrodes in successive electrode-bearing turns of the roll overlie one another, and electrically connecting a terminal to the electrodes terminating at one edge and another terminal to the electrodes terminating at the opposite edge.

3. A process as claimed in claim 2, wherein the demetallised band is such that the pitch of the pattern of electrodes increases from one end of the length of web material to the other, to take account of the increasing diameter of the roll as it is wound.

4. A process as claimed in claim 2, wherein the demetallised band follows a square key pattern course along the length of the dielectric web.

5. A process as claimed in claim 2, wherein the repeating pattern of electrodes is such as to first provide two isolated electrodes which are opposite one another and extend from opposite edges of the web, and then a single isolated electrode which does not extend from either edge but overlaps in a transverse direction the said first two electrodes, and so on alternately.

6. Apparatus for use in a process for producing from dielectric web material metallised on one face, webs of dielectric bearing a series of metallic film electrodes for winding into a roll capacitor, comprising a frame, a supply spool rotatably mounted thereon to carry a reel of thin flexible dielectric web material metallised on one face, a winding-up mandrel likewise rotatably mounted on the frame to which the dielectric web is led from the supply spool, a demetallising wheel of electrically conductive material mounted for rotation on the frame in position where the web can be led around a substantial arc of the demetallising wheel periphery with its metallised face in contact therewith on its journey from the supply spool to the winding-up mandrel, an electrode in electrical contact with the demetallising wheel, a further electrode of opposite polarity in contact with the metallised face of the web, and a high tension electrical circuit for supplying current to the electrode which circuit includes a capacitor connected in parallel across the electrodes and a current-limiting resistance connected in

series in the lead to one of the electrodes, and the de-metallising wheel having a crenellated periphery comprising a radially projecting raised rib extending circumferentially around the rim of the wheel which rib deviates in substantially regular fashion from side to side of the 5 wheel rim so that the rib which is the only part of the wheel to contact the web demetallises a devious band extending continuously along the web thereby subdividing the metallisation thereon into a series of metallic film electrodes forming a repeated pattern in which some 10

of said electrodes extend inwardly from one edge of the web and others extend inwardly from the opposite edge.
